(57) **CLAIM**

The ornamental design for a portable smart watch charger, as shown and described.

DESCRIPTION

FIG. 1 is a top, front, left side perspective view of a portable smart watch charger showing my new design;

FIG. 2 is a bottom, back, right side perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, left side perspective view of the portable smart watch charger of FIG. 1, shown in a first condition for use; and,

FIG. 10 is a top, front, right side perspective view of the portable smart watch charger of FIG. 1, shown in a second condition for use.

The broken lines in the drawings depict portions of the portable smart watch charger that form no part of the claimed design.

1 Claim, 10 Drawing Sheets
